(57) **CLAIM**

The ornamental design for a roof mount antenna, as shown and described.

DESCRIPTION

FIG. 1 is a front elevational view of a roof mount antenna showing my new design, the broken line is for illustrative purposes and forms no part of the claimed design;

FIG. 2 is a top view thereof;

FIG. 3 is a bottom view thereof;

FIG. 4 is a rear elevational view thereof; and,

FIG. 5 is a right side elevation view thereof, with the left side being a mirror image thereof.
